UNITED STATES PATENT OFFICE.

JOHN ODEN MORRIS, OF RICHMOND, VIRGINIA.

GENERATOR FOR STEAM-BOILER FURNACES.

SPECIFICATION forming part of Letters Patent No. 631,120, dated August 15, 1899.

Application filed April 14, 1899. Serial No. 713,010. (No model.)

To all whom it may concern:

Be it known that I, JOHN ODEN MORRIS, a citizen of the United States, residing at Richmond, in the county of Henrico and State of Virginia, have invented new and useful Improvements in Generators for Steam-Boiler Furnaces, of which the following is a specification.

My invention relates to generators for steam-boiler furnaces; and its object is to provide improved means whereby steam from the exhaust of an engine or live steam from a steam-boiler mixed with air can be supplied to the furnace underneath the grate for the purpose of promoting combustion of the fuel.

The object of the invention is to provide an improved construction of the same which shall possess superior advantages with respect to efficiency in operation.

The invention consists in the novel construction and combination of parts hereinafter fully described and claimed.

In the accompanying drawings, Figure 1 is a side elevation showing my improvements applied to a locomotive and tender. Fig. 2 is a detail front elevation of the locomotive. Fig. 3 is a front elevation of a stationary boiler provided with my improvements. Fig. 4 is a longitudinal section of the same. Fig. 5 is a detail perspective view of the perforated head located in the generator. Fig. 6 is a longitudinal section of the coupling connecting the generator-pipe with the steam-supply pipe.

Referring now to Figs. 1 and 2, the reference-numeral 1 designates a locomotive, and 2 the tender thereof, of any ordinary or suitable construction. Connected with the exhaust of the cylinders of the engine is a pipe 3, which extends rearwardly to the tender and is connected with a coil 4, located in the water-box of the tender for the purpose of heating the feed-water contained therein.

The numeral 5 designates a pipe connected with the pipe 3 and leading to the generator hereinafter described. This generator is the same in construction and operation whether applied to an engine-boiler or a boiler for heating or other purposes, so I will therefore describe the same as used in connection with the boilers shown in Figs. 3 and 4. Referring now to said figures, the reference-numeral 6 designates the ash-pit door, hinged to the front of the furnace, as usual, and provided with a rectangular opening through which the generator 7 passes and extends under the grate. This generator consists of a rectangular box open at both ends, and the front end, which is located outside said door, is provided with a flaring mouth or end 8. When the furnace is provided with two ash-pit doors, then two generators are employed; but as they are identical in construction and operation a description of one will suffice for both. Located in said generator is a rotatable paddle-wheel, comprising the shaft 9 and paddles 10, the latter of which are formed with openings 12 for insuring a perfect admixture of the steam and air fed to the ash-pit underneath the grate.

The numeral 13 designates a horizontal pipe located in said generator and provided with a transverse pipe 14, having perforated heads 15. The outer end of the pipes 13 is connected with a vertical pipe 17 by a coupling constructed as follows: The numeral 18 designates a nipple-screw-threaded internally and externally and formed with an angular portion 19, with which a wrench is adapted to be engaged for the purpose of screwing the same in a section 21, having a flange 22 and formed with an interior shoulder 23. Bolted to this section 21 is an upper section 25, formed with a boss 25^a, the edge of which is sharpened and bites into a washer 25^b, seated on a flange 26 at the lower end of a pipe 26^a, which is connected with the steam-boiler.

The operation is as follows: Steam from the boilers is admitted to the generator through the pipes connected therewith, which steam escaping through the perforated heads will impinge against the paddle-wheel and turning the same will tend to create a vacuum in the generator and will thus cause air to be drawn into the same and mixing with the steam will be fed to the ash-pit and grate, and thus insure complete combustion of the fuel.

When the invention is used in connection with steam-boilers for running a locomotive or other engine, I prefer to supply the generator with steam from the exhaust of the cylinders instead of directly from the boiler, as such steam is mixed with the oil or other lubricant of the cylinders, which, mixing with

the steam and air, will add still further to the efficiency of the device in promoting combustion of the fuel.

Suitable valves or cocks are to be employed wherever found desirable or necessary.

Having thus fully described my invention, what I claim is—

1. In a steam-boiler furnace, the combination with the ash-pit door having an opening therein, the generator, the steam-supply pipe extending into the generator and the pipe connected therewith by a swivel or flexible connection, of the transverse pipe connected with said supply-pipe and located in said generator, the perforated head connected therewith and the rotatable wheel provided with blades having openings therein, substantially as described.

2. In a steam-boiler furnace, the combination with the ash-pit door having an opening therein, the generator, the steam-supply pipe extending into the generator, the pipe connected therewith by a flexible connection and the exhaust-pipe extending from the cylinder and connected with said swivel connec-

tion, of the transverse pipe connected with said supply-pipe and located in said generator, the perforated head connected therewith and the rotatable wheel provided with blades having openings therein, substantially as described.

3. The combination with a steam-boiler furnace, of the ash-pit door, the generator passing therethrough, the paddle-wheel, the transverse pipe provided with a perforated head, the pipe connected therewith provided with a peripheral rim, the upper section connected therewith provided with a boss having a sharpened edge, the lower section bolted to said upper section having an enlarged upper end, the packing, the screw-threaded nipple and the supply-pipe connected therewith, substantially as described.

In testimony whereof I have hereunto set my hand in presence of two subscribing witnesses.

JOHN ODEN MORRIS.

Witnesses: BENNETT S. JONES, L. L. BURKET.
